CLAIM

The ornamental design for a propeller guard of an aircraft, as shown and described.

DESCRIPTION

FIG. 1 is a top, front, left perspective view of a propeller guard of an aircraft showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, left perspective view thereof;

FIG. 9 is a top, right perspective view thereof;

FIG. 10 is a top, rear perspective view thereof;

FIG. 11 is a bottom, rear perspective view thereof; and, FIG. 12 is another perspective view showing use state thereof.

The broken lines in FIG. 12 are for illustrative purposes only and form no part of the claimed design.
